RIDING LAWNMOWER

Theodore H. Koeber, Barrington, and Robert A. Skyer,
Chicago, Ill., assignors to International Harvester Com-
pany, Chicago, Ill., a corporation of Delaware

Filed Nov. 13, 1967, Ser. No. 9,379

Term of patent 14 years

U.S. Cl. D40—1
Int. Cl. D8—01

FIG. 1

FIG. 2

FIG. 3

FIG. 4

FIGURE 1 is a perspective view of our design for a riding lawnmower as seen from the right front side thereof;

FIGURE 2 is a side elevational view of the structure shown in FIGURE 1 of the side opposite of that seen in FIGURE 1;

FIGURE 3 is a plan view of the structure; and

FIGURE 4 is a perspective view of the structure taken from the right rear corner thereof.

The dominant features of our design reside in the portions shown in full lines.

We claim:

The ornamental design for a riding lawnmower, as shown and described.
